UNITED STATES PATENT OFFICE.

IRVING A. VEITH AND RICHARD F. ERENTAL, OF NEW YORK, N. Y.

DESIGN FOR A JAR OR SIMILAR CONTAINER.

Application filed September 23, 1925. Serial No. 14,884. Term of patent 14 years.

To all whom it may concern:

Be it known that we, IRVING A. VEITH and RICHARD F. ERENTAL, citizens of the United States, residing at New York city, county of New York, borough of Manhattan, and State of New York, have invented a new, original, and ornamental Design for Jars or Similar Containers, of which the following is a specification, reference being had to the accompanying drawing, forming a part thereof.

We claim:—

The ornamental design for a jar or similar container, as shown.

IRVING A. VEITH.
RICHARD F. ERENTAL.
